The Lowell Manufacturing Company, of the same place.

Letters Patent No 1955-Dated June 14th 1864.

Design for a Carpet Pattern.

The schedule referred to in these Letters Patent and making part of the same.

To all whom it may concern:

Be it known that I, Elmer J. Ney of Lowell, in the County of Middlesex and State of Massachusetts have originated and designed a new Pattern for Carpets or other fabrics of which the following is a full, clear and exact description, reference being had to the accompanying drawings, making part of this specification.

Figures A, A, A, A, are groups of flowers, leaves and scrolls arranged as shown in the drawings.

B, is a group consisting of a rose, one large leaf and three smaller ones.

C, D, E, F, G, H, are portions of groups similar to B.

The remainder of the design consists of a vine occupying the spaces between the specified figures.

The above specification refers to that part of the drawings enclosed by blue lines.

The colors employed for the different portions of the design, may be varied to suit the taste and wish of the manufacturer.

Claim.

What I claim as my invention, and desire to secure by Letters Patent, is the Design or Pattern for Carpets, or other fabrics herein set forth.
